UNITED STATES PATENT OFFICE.

JULIUS N. CLEMMER, OF OMAHA, NEBRASKA.

FOLDABLE BOAT.

Application filed February 20, 1923. Serial No. 620,177.

To all whom it may concern:

Be it known that JULIUS N. CLEMMER, a citizen of the United States, residing at Omaha, in the county of Douglas and State 5 of Nebraska, has invented certain new and useful Improvements in Foldable Boats, of which the following is a specification, reference being had therein to the accompanying drawings.

10 The invention relates to foldable boats, and has for its object to provide a device of this character, wherein the boat is formed from a plurality of hingedly connected sections, which sections may be folded onto 15 each other into a compact form, thereby allowing the boat to be easily shipped, or transported on the running board of an automobile.

A further object is to proportion the sections of the boat whereby the bow section 20 may be folded to a position within the midship section, and the stern section folded to a position where it will receive the other sections of the boat. Also to form the boat 25 sections in such a manner whereby upon any of the sections springing a leak the other sections will not be flooded.

A further object is to provide special 30 hinges for connecting the sections together, which hinges allow the sections to receive each other, and to provide apertured lugs carried by the adjacent ends of the boat sections, which lugs register when the boat is in extended position and receive securing 35 pins.

With the above and other objects in view 40 the invention resides in the combination and arrangement of parts as hereinafter set forth, shown in the drawing, described and 45 claimed, it being understood that changes in the precise embodiment of the invention may be made within the scope of what is claimed without departing from the spirit of the invention.

45 In the drawing: —

Figure 1 is a top plan view of the boat.

Figure 2 is a side elevation of the boat.

Figure 3 is a vertical longitudinal sectional view through the boat, showing the 50 same folded.

Figure 4 is a detail side elevation of the adjacent ends of boat sections, showing the lugs carried thereby.

Referring to the drawing, the numeral 55 1 designates the bow section of the boat, 2 the midship section, and 3 the stern section.

The bow section 1 is smaller than the chamber 2^a of the section 2, and is adapted to be folded to a position where it will be received in the chamber 2^a as shown in Figure 3, after which the stern section 3 is folded to a position where it will receive in the chamber 3^a thereof the folded sections 1 and 2, as shown in Figure 3. The sections 1, 2 and 3 may be formed from any kind 60 of material, however they are provided with transversely disposed walls 4, which engage each other, and which, in case of puncture of any of the sections, water will not flow into adjacent sections, thereby allowing the boat 65 to be rowed or otherwise propelled to the shore. The sections 1 and 2 and 3 are connected together by means of hinges 5, which hinges are secured at 6 in the bottoms of the sections 2 and 3. Hinges 5 comprise 70 upwardly extending sections 7, which are hingedly connected at 8 adjacent the bottoms of the sections, hingedly connected sections 9, which are hingedly connected at 10 to the upper ends of the sections 7; the 75 sections 7 and 9 when extended being substantially the length as the height of the walls 4, and are provided with angularly disposed portions 11, which engage over the upper sides of the walls 4, as clearly shown 80 in Figure 2. The angularly disposed portions 11, are in turn hingedly connected at 12 to brackets 13 secured to the inner sides of walls 4 of the section 2 and the section 1, therefore it will be seen by referring to 85 Figure 2, that when the boat sections are extended, the walls 4 will engage each other 90 and the hinges will allow freedom of movement during the folding operation for the sections to be positioned within each other 95 as shown in Figure 3.

The adjacent ends of the sections 1, 2 and 3 are provided with apertured lugs 14, which lugs, when the sections are in abutting engagement as shown in Figure 2, register and receive securing pins 15, which 100 securing pins hold the sections rigidly together. The pins 15, when the bolt is folded, are removed.

The boat may be propelled in any suitable manner, such for instance as by an engine or by oars, and removable seats of any type may be used.

From the above it will be seen that a foldable boat is provided, which is simple in 110 construction, and constructed in such a manner that the sections thereof may be folded

onto each other in such a manner that the boat may be formed into a compact package for transportation, particularly on the running board of an automobile.

5 The invention having been set forth what is claimed as new and useful is:—

A boat comprising a bow section, a midship section and a stern section, said sections having their adjacent ends provided 10 with transversely disposed walls adapted to engage each other, hinges pivotally connected in the bottoms of the midship section and the stern section, said hinges extending upwardly and terminating in an-

gularly disposed portions hingedly connect- 15 ed to brackets carried by the midship sec-
tion and the bow section and hinged at a
point above the walls, the upwardly ex-
tending hinges being formed from hingedly
connected sections hingedly connected in- 20
termediate the ends of the hinges, and aper-
tured lugs carried by the adjacent ends of
the sections and adapted to overlie each
other when the sections are in extending
portion and receive securing means. 25

In testimony whereof I hereunto affix my
signature.

JULIUS N. CLEMMER.
